UNITED STATES PATENT OFFICE.

GEORGE E. HOMER, OF BOSTON, MASSACHUSETTS.

DESIGN FOR A MATCH-SAFE OR SIMILAR ARTICLE.

SPECIFICATION forming part of Design No. 37,187, dated October 18, 1904.

Application filed September 8, 1904. Serial No. 223,789. Term of patent 7 years.

To all whom it may concern:

Be it known that I, GEORGE E. HOMER, a citizen of the United States, residing at Boston, in the county of Suffolk, State of Massachusetts, have invented a certain new, original, and ornamental Design for a Match-Safe or Similar Article, as shown in the accompanying drawings.

Figures 1 and 2 of the said drawings show, respectively, the opposite sides of a match-safe embodying my design.

What I claim as new, and desire to secure by Letters Patent, is—

The ornamental design for a match-safe or similar article as shown.

GEORGE E. HOMER.
